UNITED STATES PATENT OFFICE

148,163

DESIGN FOR A STATUETTE

Walter E. Heaberlin, Kansas City, Mo.

Application February 17, 1947, Serial No. 136,952

Term of patent 3½ years

(Cl. D29—23)

To all whom it may concern:

Be it known that I, Walter E. Heaberlin, a citizen of the United States, residing at Kansas City, in the county of Jackson and State of Missouri, have invented a new, original, and ornamental Design for Statuette, of which the following is a specification, reference being had to the accompanying drawings, forming part hereof.

Fig. 1 is a front elevation of a statuette, showing my new design.

Fig. 2 is a perspective view of the statuette.

Fig. 3 is a side elevation of the statuette.

Fig. 4 is a plan view of the statuette.

I claim:

The ornamental design for a statuette, as shown.

WALTER E. HEABERLIN.
